UNITED STATES PATENT OFFICE.

CARL MUEHLEISEN AND CHRISTIAN AUGUSTUS ALBRECHT, OF BERLIN, GERMANY,
ASSIGNORS TO MERGENTHALER LINOTYPE COMPANY, OF NEW YORK, N. Y.

MEANS FOR LEVELING MULTIPLE-FACE MATRICES IN LINE-CASTING MACHINES.

1,017,444.

Specification of Letters Patent. Patented Feb. 13, 1912.

Application filed April 5, 1910. Serial No. 553,564.

To all whom it may concern:

Be it known that we, CARL MUEHLEISEN and CHRISTIAN AUGUSTUS ALBRECHT, citizens of the United States of America, and 5 residing, respectively, at No. 88 Chausseestrasse and No. 23 Chausseestrasse, Berlin N. 4, in the Empire of Germany, have invented new and useful Improvements in Means for Leveling Multiple-Face Matrices 10 in Line-Casting Machines, of which the following is a specification.

This invention relates to improvements in means for leveling multiple face matrices in line casting machines, after casting from 15 and preparatory to distributing said matrices. It is especially applicable to the line casting machine which is known commercially under the trade mark "linotype," described in the specification of Letters Patent 20 No. 436532 dated September 16th 1890. For that reason, the application of it to that machine, has been chosen as an example convenient for illustration and specification as to details.

25 When the matrices in the composed line, have (as described for example in Letters Patent Nos. 547633 and 615909) two or more faces one above another, they are supported in the so-called first elevator of the machine 30 at as many different levels, and this difference in level must be maintained until the respective printing bar has been cast. After it has been cast, the matrices must all be restored to a common level in order that they 35 may be transferred from the first elevator to the second elevator, the latter having only one level and being the first organ of the distributing mechanism.

According to the present invention, the 40 matrices to be leveled (*i. e.*, restored to the common or normal level) are positively pushed upward in a straight path, past a yielding ledge, which, by such up-lifting of the said matrices, is momentarily moved out 45 of the path of the adjacent lugs of the matrices and immediately thereafter moved beneath the said lugs to support all the matrices of the line at the common level.

In the accompanying drawings:—Figures 50 1 and 2 are vertical sections illustrating one arrangement according to this invention, and respectively showing the device at dif-

ferent stages of operation, and Fig. 3 is a vertical section of a modified construction of the device.

55

1 represents the head or upper part of the first elevator; 2, one of the matrices in the higher or normal position in the said elevator; 3, the supporting ledge of those higher matrices, and which, according to 60 the present invention, is movable relatively to the elevator head 1; 4, one of the matrices in the lower or variant position; 5, the mold against which the elevator is holding the composed line in the casting position; 6, a 65 bar or matrix-lifter in a cavity 7 in the elevator head 1, and fast to one arm of a lever 8 fulcrumed at 9, and engaging under the adjacent top lugs 10 of the matrices 4, the opposite arm of the lever 8 projecting beyond the front of said elevator; 11, a stop 70 adjustable in the fixed frame 12 of the machine and standing in the path taken by the forwardly-projecting arm of the lever 8 as the elevator 1 ascends from the casting position to meet the second elevator; 13, a spring 75 to return the matrix-lifter 6 to its normal position; 14, a bevel or cam on the bottom edge of the ledge 3; and 15, a bevel upon each of the coöperating lugs of the matrices 80 2, 4.

The foregoing description applies equally well to both of the two arrangements shown in the drawings, these arrangements differing only as regards the manner in which the 85 respective ledges 3 are rendered movable. Thus, in the arrangement shown in Figs. 1 and 2, the ledge 3 is fast to the lower end of a vertical arm 16 which extends up into a recess 17 formed in the elevator head 1 and 90 which is pivoted therein by means of a pivot rod 18; the back of the recess 17 forms a stop for limiting the rearward swing of the ledge 3 and a spring 19 pocketed partly in the arm 16 and partly in the head 1 serves 95 normally to hold the ledge in its rearmost position.

In the arrangement shown in Fig. 3 the ledge 3 is in the form of a flat plate capable of sliding horizontally forward and backward in the elevator head 1, and is normally held in its rearmost position by a blade spring 20 secured to the front of the said head, a suitable stop, not shown in the

100

drawing, being provided for limiting the rearward movement of the ledge to the desired extent.

- When the first elevator of either of the 5 two before-described arrangements is in the position in which it receives the composed line of matrices from the assembler, and when such matrices are moved thereinto, those of the matrices which are to present 10 their lower formative cavities or faces to the mold 5, that is to say, the "normal" matrices 2, are received upon—or, more definitely stated, have their front bottom lugs received upon—the ledge 3, which serves for 15 supporting them during the casting operation, while those of the matrices which are to present their upper faces to the mold, that is to say the "variant" matrices 4, are received upon—or more definitely stated, have 20 their upper lugs received upon the ordinary ledge 21 and the bar or matrix-lifter 6 respectively, and they will remain in that position relatively to the elevator 1 throughout the casting operation.
- 25 When the elevator 1 moves away from the casting position, in which it is shown in Fig. 1, and as it approaches the second elevator, the lever 8 engages with the stop 11 whereby the matrix-lifter 6 is raised relatively to the elevator head 1, from the position in which it is shown in Fig. 1 to that in which it is shown in Figs. 2 and 3. As the matrix-lifter 6 is thus caused to move, it raises the matrices 4, the bevels 15 on 30 which, engage with the bevel or cam 14 on the underside of the ledge 3, which latter is thereby moved forward against the action of the spring 19 Figs. 1 and 2, or 20 Fig. 3. When the matrix lifter 6 has completed its 35 rise, as in Fig. 2 or Fig. 3, the lower front lugs of the matrices 4 raised by it, have been moved past the ledge 3 which, immediately thereafter, moved by its spring 19 or 20, into its rearmost position, beneath the lower 40 front lugs of all the matrices 2, 4. After the matrices have been moved out of the first elevator 1, the latter descends and the lever 8 being thereby moved out of contact with the stop 11, the spring 13 returns the matrix-lifter 6 to its lowest position within the 45 recess 7 the bottom of which latter forms the stop for limiting the said movement in such recess.
- The terms "matrix" and "matrices" are 50 to be read as including type dies; and the term "elevator" as including any conveyer or means for moving the composed line toward the distributing mechanism, irrespective of its direction of motion.
- 60 Having described our invention, we claim and desire to secure by Letters Patent:—
1. In a line casting machine, the combination of matrices adapted to stand at a plurality of levels, a movable member for supporting them, a member distinct from said

supporting member for shifting matrices to a different level, and a single means for actuating said shifting member and for moving the supporting member out of its normal position.

2. In a line casting machine, the combination of matrices adapted to stand at a plurality of levels, a movable member for supporting them, a member distinct from said supporting member for shifting matrices to a different level, and a single means for positively actuating said shifting member and for moving the supporting member out of the path of the matrices. 70

3. In a line casting machine, the combination of matrices and a movable device for supporting them, with matrix leveling means acting through the matrices to move the supporting device out of their path. 80

4. In a line casting machine, the combination of matrices adapted to stand at a plurality of levels, a movable member for supporting them, and a matrix leveling member distinct from said supporting member but adapted also to cause the movement of the supporting member out of the path of the matrices. 85

5. In a line casting machine, the combination of matrices adapted to stand at a plurality of levels, a movable member for supporting them, and a matrix shifting member distinct from said supporting member, the whole so arranged that said matrices are shifted from one level to another and the supporting member is moved out of their path. 90

6. In a line casting machine, the combination of a movable supporting ledge adapted to support a series of matrices, a matrix leveling member distinct from said ledge, and a single means adapted to actuate the matrix leveler to move the matrices from one level to another and simultaneously to move the supporting ledge out of their path. 105

7. In a line casting machine, the combination with a matrix lifter adapted to raise matrices up to the normal level, and a ledge adapted to support matrices at the normal level, of means adapted to render the ledge resilient against the pressure thereon of the matrices and to return the ledge to normal position after the pressure of the matrices is withdrawn. 110

8. In a line casting machine, the combination with a conveyer adapted to convey matrices toward the distributing mechanism, of a matrix lifter adapted to raise matrices in the conveyer up to the normal level, a ledge adapted to support matrices at the normal level, and means adapted to yieldingly hold the ledge in the upward path of the lower matrices. 120

9. In a line casting machine, the combination with a conveyer adapted to convey matrices toward the distributing mechanism, of 125

- a matrix-lifter adapted to raise matrices in the conveyer in a straight path up to the normal level, a ledge adapted to support matrices in the conveyer at the normal level, 5 means adapted to yieldingly hold the ledge in the upward path of the lower matrices, and the ledge being suitably formed to be engaged by the matrices for moving the ledge out of their path.
- 10 10. In a line casting machine, the combination with a conveyer adapted to convey matrices toward the distributing mechanism, of a matrix-lifter adapted to raise matrices in the conveyer in a straight path up to the 15 normal level, a movable ledge adapted to support matrices in the conveyer at the normal level, and means adapted to hold the ledge in the upward path of the lower 20 matrices.
11. In a line casting machine, the combination with a conveyer adapted to convey matrices toward the distributing mechanism, of a matrix-lifter adapted to raise matrices in the conveyer in a straight path up to the 25 normal level, a movable ledge adapted to support matrices in the conveyer at the normal level, means adapted to hold the ledge in the upward path of the lower 30 matrices, and a cam on the ledge adapted to be engaged by the matrices for moving the said ledge out of their path.
12. In a line casting machine, the combination with a conveyer adapted to convey matrices toward the distributing mechanism, 35 of a matrix-lifter adapted to raise matrices in the conveyer in a straight path up to the normal level, a movable ledge adapted to support matrices in the conveyer at the normal level, a spring in operative relationship 40 to the ledge to hold the latter in the upward path of the lower matrices, and a cam on the ledge adapted to be engaged by the matrices for moving the said ledge out of their path.
13. In a line casting machine, the combination with a conveyer adapted to convey matrices toward the distributing mechanism, 45 of a matrix-lifter adapted to raise matrices in the conveyer up to the normal level, a ledge adapted to support matrices in the conveyer at the normal level, a 50 guide where-
- in the ledge is free to slide so that it can move into and out of the upward path of the lower matrices, and means adapted to hold the ledge in the said path. 55
14. In a line casting machine, the combination with a conveyer adapted to convey matrices toward the distributing mechanism, of a matrix-lifter adapted to raise matrices in the conveyer up to the normal level, a 60 ledge adapted to support matrices in the conveyer at the normal level, a guide wherein the ledge is free to slide so that it can move into and out of the upward path of the lower matrices, and a spring adapted to 65 yieldingly hold the ledge in the said path.
15. In a line casting machine, the combination with a conveyer adapted to convey matrices toward the distributing mechanism, of a matrix-lifter adapted to raise matrices 70 in the conveyer up to the normal level, a ledge adapted to support matrices in the conveyer at the normal level, a guide wherein the ledge is free to slide so that it can move into and out of the upward path of 75 the lower matrices, a spring adapted to yieldingly hold the ledge in the said path, and means operative by the ascending matrices adapted to move the ledge out of that 80 path.
16. In a line casting machine, the combination with a conveyer adapted to convey matrices toward the distributing mechanism, of a matrix-lifter adapted to raise matrices in the conveyer up to the normal level, a 85 ledge adapted to support matrices in the conveyer at the normal level, a guide wherein the ledge is free to slide so that it can move into and out of the upward path of the lower matrices, a spring adapted to 90 yieldingly hold the ledge in the said path, and a cam surface on the ledge adapted to be engaged by the matrices for moving the ledge out of their path. 95

In witness whereof we have hereunto set our hands in the presence of two witnesses.
